No. 279,101.

Patented June 5, 1883.

UNITED STATES PATENT OFFICE.

DANIEL McPHERSON, OF CALEDONIA, NEW YORK.

GRAIN-BINDER.

SPECIFICATION forming part of Letters Patent No. 279,101, dated June 5, 1883.

Application filed February 28, 1883 (Model.)

To all whom it may concern:

Be it known that I, DANIEL McPHERSON, of Caledonia, county of Livingston, and State of New York, have invented a new and useful Improvement in Grain-Binders, of which the following is a full, clear, and exact description, reference being had to the accompanying drawings, making part of this specification.

My invention relates to a novel means for separating the gavel to be bound from the incoming grain, and for taking up the slack in the band; to the means for taking the cord from the needle and carrying it into the notched cord-holding disk or wheel; to the means for lifting the portions of the band extending around the bundle down past the knotter, and between said knotter and the cord-holder above the knotter for throwing the cord over the head of the revolving knotter and forming the loop, and to the means for simultaneously lifting the cord-holder for giving the necessary slack for forming the loop in the ends of the band; to the means for imparting a backward throw to the cord-holder for carrying the cord properly into the cord-grasping hook of the knotter-head in the process of raising the cord-holder for giving the necessary slack to form the loop, and for actuating and guiding the vertical movements of the cord-holder carrier, whereby the first movement of the latter in descending is in a vertical path for taking up the slack in the band, and avoiding the displacing of said band until the latter has been grasped by the knotted hook or jaw of the knotter; and to the combination, with said cord-holder carrier and knotter, of a rotating knife and loop-stripper, the movement of which is so timed relatively to those of the knotter, hook, and cord-holder carrier as to cut the cord after the slack has been taken out of the knot, and the ends of the band have been grasped by the knotter-hook of the knotter; to the means for shifting the cord from one side to the other of the vibrating hook or arm which takes the cord from the needle and carries it into the cord-holder, and to certain details of construction and arrangement hereinafter described.

In the accompanying drawings, Figure 1 represents an elevation of my improved knotting mechanism, taken from the stubble side of the machine. Fig. 2 is a front elevation,

and Fig. 3 is a rear elevation, of the same. Fig. 4 represents a vertical longitudinal section in line with the shaft of the knotter. Fig. 5 is a side elevation of the knotter detached, with its actuating-pinions and hollow shaft in section. Fig. 6 is a top plan view of the knotter, and Fig. 7 is a bottom view of the same. Fig. 8 shows in perspective the upper end of the 60 knotter-shaft standard, with its cam for actuating the knotter-hook. Fig. 9 is a rear elevation of the toothed disk actuating the knotter, and Fig. 10 is a similar elevation of the toothed segment actuating the revolving knife 65 and loop-discharger.

The mechanism employed for actuating the knotter is similar to that described in Letters Patent granted to me March 5, 1878, No. 200,868, and the needle has an orbital movement imparted to it in a manner and by mechanism similar to that described in Letters Patent granted to me January 4, 1881, No. 236,347, and these features, therefore, need not be described in detail further than is necessary to explain my present improvements and their connection with said parts.

A A' represent uprights of the frame of the elevator, by means of which the grain is carried over the main drive-wheel to a concave 80 receiver or binder-table on the outer side of said wheel, said frame and elevator, together with the reaping-machine to which they are connected, being of any usual or preferred construction.

B B' represent an upright rectangular frame, in which the binding mechanism is mounted or supported, said frame being suspended on the outer side of the drive-wheel upon pivots at a and a', connecting it at its upper inner 90 corners with the upper ends of the uprights A and A' of the elevator-frame, the arrangement being such that the binder-frame can be turned over upon the elevator for transportation or for passing through narrow gates or passages. 95 The lower and inner longitudinal timber, B', of the binder-frame has its ends extended to form stops b b, which rest against the lower ends of the uprights A and A', and serve to prevent said frame from swinging inward beyond a proper working position when in use. The upper part of the frame B B' is provided with suitable bearings for the mechanism through which an orbital movement is im-

parted to the needle C, which movement and mechanism, being similar to that described in my patent of January 4, 1881, above referred to, need not be here described. To the upper 5 end of this needle is pivoted a pendent rod, C', forming a grain-separator and cord take-up for separating from the gavel to be bound and crowding backward therefrom the grain coming into the concave receiver behind the needle after the latter has passed down through 10 the grain for carrying the cord to the knotter, and also for taking up the slack in said cord. This rod C' rests against the rear face of the needle C, its lower end by preference resting 15 in a groove in the lower end of said needle in such manner as to adapt both to pass down through the grain together and prevent the grain from getting between them. The cord or other band material passes from a spool ar- 20 ranged on the inner side of the frame B through an eye, c, in the needle, thence through an eye, c', in the point of the take-up rod C' and back through an eye at c' in the point of the needle C, and thence to the cord-holder underneath 25 the grain-receptacle, hereinafter described. Upon a transverse bar, B', of the frame B, at or near the center of its length, is secured a stop-pin or standard, b', and the separating-rod C' is provided on its side, near its upper 30 end, with a pin, c', which, as the needle is carried downward and outward for carrying the cord to the cord-holder, comes in contact with the stop b', and serves, as the outward movement of the needle C is continued, to impart a 35 positive movement to the lower end of the rod C' for moving the incoming grain back or inward away from the outwardly-moving needle, and also for taking up any slack in the band. The rod C' is retracted into its former position 40 against the needle, when released from the stop b', by a spring, c'', surrounding the pivot through which it is connected with the needle. A grooved cam or other suitable means may be substituted for the stop and spring for imparting the movements described to the rod C'. 45

D is an upright rectangular frame, in which the knotting devices and their actuating mechanisms are mounted, said frame being rigidly secured at its lower end to the outer longitudinal timber or flooring of frame B. This frame is provided with bearings for a longitudinal driving-shaft, E, and at its upper end with a vertical sleeve, B', forming a bearing for the tubular shaft F of the knotter, the inner solid shaft, F', having its bearings in the tubular shaft. The shaft E serves to actuate the binding mechanism, and is geared to and actuated from the main drive-wheel of the reaper in any suitable manner. Other shafts hereinafter de- 50 scribed have also their bearings in suitable lugs or arms of the frame D.

Upon the shaft E is secured a cam and gear wheel, G, upon which are formed a number of toothed segments and a cam and pin or eccentric, for purposes which will be explained. 65

The frame D is provided with arms to form bearings for a short shaft, E', on which a spur

gear or segment, G', engaging with and actuated from a toothed segment, g, on the wheel G, is secured, said shaft E' being provided on its forward end with a crank-arm, e, the wrist-pin e' of which enters a horizontal slot, h, in an arm of a sliding plate, H. This plate H is provided also with upright slots h' and h'', vertical in their lower portions and inclined or curved 75 outward from the knotted at their upper portions, through which slots the plate H is secured to the forward standard of the frame D by headed pins which permit the vertical and lateral or inward and outward movement of the 80 plate H, actuated by the crank-pin e' and guided by the form of the slots h' and h''. The upper end of the plate H is provided at h'' with bearings for the horizontal shaft of a rocking finger, f, which projects inward within the path of 85 the needle C. This projecting finger is made in angular or crank form, and its point is acted upon by an incline formed at c' on the side of of the needle, the point of the finger serving to take the cord from the needle, and then, be- 90 ing rocked toward the knocker by the latter, to carry said cord to and into the cord-holding devices. The finger f, after it escapes from the needle, is retracted to its former position, for adapting it to again seize the cord, by a 95 spring, f', surrounding its shaft f'.

The cord-holding device consists of a forked arm, h', formed upon or secured to the upper end of plate H, at its inner edge, and a toothed cord-holding wheel and attached ratchet-disk, 100 i, mounted in bearings in the fork of said arm. To the forward face of the plate H is pivoted an arm, I, provided with a projecting pin, i', which is acted upon, once in each revolution of the shaft E, by a cam or eccentric, E'', fast on 105 said shaft in front of the frame D. To the swinging end of the arm I is pivoted a pawl, I', the outer or free end of which engages the ratchet-disk i, and serves to move or rotate said disk a distance equal to the length of one 110 tooth of the cord-holding wheel at each throw of the pawl. The pawl is retracted for repeating the operation by any suitable arrangement of stop on the frame D, said stop acting on the pin i' near the upper end of the throw of plate 115 H. The rocking movement of the cord-finger f described carries the cord in between the teeth of the cord-holding wheel, and the movement of the latter, as described, carries said cord in between said wheel and the sides of 120 the forked arm h', thereby grasping and holding said cord. In this movement the portion of the cord grasped by said toothed wheel, and extending therefrom to the point of the needle, will pass underneath and outside or forward of 125 the finger f, and to get this back of or behind said finger I provide the cam E' on its forward face with an arm, E', having perforated lugs e' e', in which is mounted a rock-shaft, E'', having at its inner end, adjacent to the shaft E, a 130 forwardly-projecting arm, e'', which, at each revolution of the shaft E, comes in contact with a fixed standard, J, secured to the frame B, and which serves to rock the shaft E'' in its

bearings e^1 . The outer end of this shaft E^1 is provided with a rearwardly-projecting finger, e^2 , which overrides the cord-finger f , and serves to carry the cord inward toward the knotter until it clears the point of said finger, when the tension on said cord draws it into proper position behind the finger f .

In suitable flanges on the frame D , on the inner side of the knotter-shafts F and F' , ways are formed, in which a vertically-reciprocating rod, k , moves, actuated through an angular foot, k' , on its lower end, and a pin, k'' , on the rotating cam and gear wheel G , once in each revolution of the latter. The upper end of this rod has a curved arm, k^1 , formed upon or secured to it, which extends partly around the knotter-shaft, underlying the portion of cord extending between the cord-holding wheel and the knotter, for a purpose which will be explained.

L is a vertical rock-shaft mounted in suitable bearings in outwardly-projecting arms of the frame D , and provided near its lower end with an inwardly-projecting arm, L' , which is acted upon by a cam, l , on the wheel G , for rocking said shaft L . The shaft L has an arm, L' , on its upper end, which, by the rocking movement of the shaft, serves to carry the portions of the band lying between the cord-holding wheel and the bundle in within reach of the cord grasping and looping hook on the knotter, as hereinafter explained.

M is an upright shaft mounted in suitable bearings on the rear standard of the frame D , and provided near its lower end with a bevel-pinion, m , which projects through an opening or slot in the rear upright or standard of frame D , and engages with a beveled segment, m' , on a plate or disk, M' , fast on the shaft E , and which at each revolution serves to impart a single revolution to the pinion m and shaft M . A plate, m^2 , on the shaft M , below the pinion m , provided with a flattened surface on one side, which rests against the adjacent face of the disk M' in the intervals between the action of the segment m' on the pinion, serves to prevent accidental displacement of the pinion m and shaft M and to hold them in proper position to be acted upon by the segment m' on its next round.

To the upper end of the shaft M is secured an arm, M^2 , of a length sufficient to enable it to reach over the knotter, moving in close proximity thereto, and provided at its outer swinging end with an angular extension, m^3 , terminating at its lower end in a knife or cutter, m^4 , the office of which arm and cutter is to cut the cord and simultaneously to slip the loop off the jaws of the knotter and over the ends of the cord grasped by the knotter-hook, as will be explained. The arm m^2 sweeps over the knotter, and the pendent or angular extension m^3 thereof serves to support the knife m^4 below the plane of said head and to bring said arm into proper relation to the hooks or jaws of said knotter to push off the loop.

The knotter is composed of three parts—viz.,

the cap part or head N , rigidly secured to the upper end of the inner shaft, F , the cord grasping and looping hook N' , rigidly secured to the outer tubular shaft, F , and a second or knotting hook, N^2 , pivoted to and revolving with the grasping and looping hook N' , but adapted, through its pivotal connection therewith, to receive a lateral independent vibrating movement for enabling it to grasp and hold the end portions of the band to be drawn through the loop in forming the knot. The hook N^2 is provided (see Fig. 7) at or near the center of its length (from its pivot to its point) with an inwardly-projecting spur, n , which prevents the cord from being carried too far back between the hooks N' and N^2 . The hook or pivoted jaw N^2 is further provided on its heel extension, beyond its pivotal connection with the hook N' , with a pendent pin carrying a friction-roller, n' , which works in a cam-groove formed on the upper end of the sleeve-standard D' . (See Fig. 8.) This cam is double-walled, consisting of an inner wall, p , crescent-shaped and partially surrounding the knotter-shafts, for acting upon the friction-roller n' to close the hook N^2 on the hook or jaw N' , and an outer wall, p' , on the sleeve-bearing D' , opposite the part of least eccentricity of the cam p , for crowding said roller inward toward the knotter-shafts and opening the hook or jaw N^2 . This outer wall, p' , of the cam-groove is shown detached from the sleeve-standard D' , and adapted to be secured thereto by means of a screw or equivalent fastening passing through a perforated lug or ear, p'' , into said sleeve-standard at b' ; but it may be formed in one piece with the standard or applied thereto in any preferred manner. The cap portion or head N of the knotter is partly cut away on one side, and has a pendent lip or jaw at n^2 , between which and the hook or jaw N' the cord is grasped, and is by preference made convex on its upper face to facilitate the forming and clearance of the loop.

Motion is imparted to the knotter by means of beveled pinions F^2 and F^3 on the lower end of its shafts F and F' , respectively, engaging with toothed segments on the wheel G , as follows, viz: at g' a short segment of sufficient length to give a quarter-revolution (more or less) to the pinion F^2 , shaft F , and hook or jaw N' for adapting it to close against the jaw n^2 for grasping the two strands of the cord reaching from the holder around the bundle; a long segment at g^2 , with the teeth of double the width of the teeth of segment g' , for actuating both pinions F^2 and F^3 simultaneously and imparting three-quarters of a revolution (more or less) to the entire knotter for forming the loop in the cord; and another short segment at g^3 for giving a quarter-revolution to the shaft F' and its cap or head N for carrying forward the jaw n^2 and opening the hook N' for releasing the cord and leaving the hook N' open preparatory to forming a new loop. The concave receiver or table which receives the grain from the elevator and in which the grain is bound will have

a transverse slot formed in it, permitting the passage of the needle in carrying the cord around the grain therein to the cord grasping and holding disk or wheel.

5 The operation is as follows: Supposing one end of the cord to be held in proper position by the cord-holding wheel, and the cord by the orbital movement of the needle to have been carried around the grain in the concave receptacle, the rod C' and the cord-finger f, acting as hereinbefore described, the former for separating the grain and drawing the cord tightly around the bundle, and the latter for picking the cord off the needle and carrying it into the cord-holding wheel, by the rotation of which it is seized, as explained. Thus the two ends of the band surrounding the bundle in the concave receptacle are held by said wheel. At this instant the arm L² is vibrated 10 to carry the portions of said cord extending between the concave and the cord-holding wheel to within the sweep of the hook or jaw N', which is now carried through a quarter of a revolution by the action of the segment g' on 15 the pinion F², causing the cord to be grasped by the knotter between said hook and the jaw n² of the cap or head N. At this instant, and in the interval of rest given to the knotter, due to the space on wheel G between the segments g' and g², the curved arm k², underlying 20 the cord between the knotter and the cord-holding wheel, is lifted by the action of the pin k'' for raising that portion of the cord lying between the holder and knotter and throwing it 25 over and above the knotter. At this point, the double-width segment g'' having reached the knotter-shaft pinion, the knotter is started on a movement of three-quarters of a revolution, more or less, the cord-holding wheel holding 30 the ends of the band having in the meantime been lifted through the action of the crank-pin e' on the plate H for supplying the necessary slack for forming the loop. As the knotter begins its movement described the 35 hook or jaw N² is opened by the action of the cam-wall p', and the cord-holding wheel begins its downward movement in a vertical path for drawing the loop tight, and at the same time holding the cord extending from over the cap 40 or head N in position to be grasped between the hook N² and the hook N' before the knotter completes its three-quarter revolution referred to, and said hook is closed upon the cord by the action of the inner wall, p, of the cam 45 thereon. The downward movement of the cord-holder is first in a direct vertical path, due to the form of the slots h' and h², to avoid drawing the cord out from between the jaws or hooks N' and N² in taking up the slack prior 50 to the closing of said jaws or hooks one on the other. At or about the instant the jaws N' N² have closed firmly on the cord the segment g² acts on the pinion F³ and shaft F', carrying 55 forward the jaw n² a quarter-revolution, opening the hook N', and at the same time, the arm k² having been released from the action of the 60

pin k'' and removed out of the path of the arm M², the latter is caused to rotate, carrying the knife m⁴, the latter cutting the cord below the plane of the knotter and between said knotter 70 and the cord-holding wheel, the pendent arm, to which the knife m⁴ is attached, at the same instant slipping the loop over the ends or points of the hooks N' and N², and over the ends of the band grasped and held between 75 said hooks, as explained, and which are thus drawn through the loop, forming the knot.

Having now described my invention, what I claim as new is—

1. The combination, with the needle, of a 80 combined vibrating grain-separator and cord-take-up rod pivoted to and moving with said needle, and means for intercepting the rod, so that the continued forward movement of the needle shall impart a positive backward movement to the swinging end of said take-up rod, 85 substantially as and for the purpose described.

2. The hook or finger for taking the cord from the needle and carrying it to the cord-holder, made in the form of an angular or crank 90 extension of a rock-shaft, in combination with an incline on the needle for rocking said shaft and finger, substantially as described.

3. The horizontally-rotating knotter, in combination with the cord-holder, means for imparting a vertical and laterally-reciprocating movement to said holder, the intermediate vertically-reciprocating cord-lifter, and means for actuating said lifter, substantially as described. 95

4. The combination, with the rotating knotter adapted to rotate in a horizontal plane, of the cord-lifting arm k², the notched cord-holding disk or wheel, and means for imparting a vertical and laterally-reciprocating movement to said cord-holder, substantially as and for 100 the purpose described.

5. The notched cord-holding disk or wheel, in combination with the slotted plate H, provided with the curved or angular slots h' and h², and means for vibrating said plate and cord-holding disk, substantially as described, whereby a vertical and an oblique lateral reciprocating movement are imparted to said cord-holder, substantially as and for the purpose 110 described. 115

6. The combination, with the rotating knotter, of the cord-holder, means for imparting a vertical and laterally-reciprocating movement to said holder, the reciprocating cord-lifter, the horizontally-rotating stripper-arm, and the knife suspended from said stripper-arm, all 120 substantially as described.

7. The combination, in a knotter, of the cap or head N, provided with the pendent jaw n², the cord grasping or looping hook or jaw N', and the pivoted knotting-hook N², with its inwardly-projecting spur n', arranged and operating substantially as described. 125

8. The combination, with the concentric shafts F and F', and mechanism for actuating 130 said shafts, of the cap or head N, cord grasping or looping hook or jaw N', knotting-hook

N^o, and cam $p p'$, for actuating the latter hook, all arranged and operating substantially as described.

9. The combination, with the cord-holder 5 and the cord-deflecting finger or hook f , for taking the cord from the needle and carrying it to the cord-holder, of the rotating and rocking arm or finger e^s , for transferring the cord from one side to the other of said finger, and

means for actuating said finger e^s , substantially 10 as described.

In testimony whereof I have hereunto set my hand this 20th day of February, A. D. 1883.

D. McPHERSON.
